UNITED STATES PATENT OFFICE.

JOHN L. POLK, OF LA GRANGE, ILLINOIS.

ELECTRICAL BINDING TERMINAL.

Application filed February 9, 1925. Serial No. 7,986.

My invention relates to improvements in electrical binding terminals, and it consists in the combinations, constructions, and arrangements herein described and claimed.

5 An object of my invention is to provide an electrical binding terminal of the character described to which a multiplicity of wires or conductors may be connected at the same time and in which electrical contact between 10 each of the conductors and the terminal will be uniform and positive.

A further object of my invention is to provide an electrical binding terminal of the character described in which conductors may 15 be connected with the terminal intermediate their length without necessitating the severing of the conductors as in any binding terminals of the ordinary type.

A further object of my invention is to provide 20 an electrical binding terminal of the character described in which there are no removable parts to become lost as in the case of the ordinary binding screw terminal.

A further object of my invention is to provide 25 an electrical binding terminal of the character described that is simple in construction, neat in appearance and thoroughly efficient for the purpose intended.

Other objects and advantages will appear 30 in the following specification, and the novel features of the invention will be particularly pointed out in the appended claim.

My invention is illustrated in the accompanying drawings forming a part of this application, in which

Figure 1 is a sectional view of an embodiment of my invention,

Figure 2 is a sectional view along the line 2—2 of Figure 1,

40 Figure 3 is a sectional view of a modified form of my invention,

Figure 4 is an elevation of another modified form of my invention, and

45 Figure 5 is an elevation of still a further modified form of my invention.

In carrying out my invention I make use of an insulating instrument panel 1 or other suitable support for the binding terminal. This panel 1 is provided with a transverse 50 opening 2 therethrough, through which the lower end of a metal post 3 is projected. This end is threaded as shown at 4.

The post 3 is held in place upon the panel 1 by the provision of binding nuts 5, one on 55 either side of the panel disposed upon the threaded portion 4 of the post.

The upper end of the post 3 (see Figure 1) is in the form of a mushroom head 6. The lower peripheral edge of the head 6 (see Figure 1) is provided with a plurality of spaced apart transverse grooves 7. These grooves 7 are substantially the contour of an electrical conducting wire of average size. I prefer to have the grooves about 5/64 of an 60 inch wide.

65 A collar 8 having somewhat the form of the head 6 but inverted is disposed concentric with the post 3 and is free to move vertically upon the post. The collar 8 has its upstanding side walls 9 concentric with and close to the depending side wall portions of the mushroom head 6.

A compression spring 10 is disposed concentric with the post 3 and bears against the adjacent binding nut 5 and the adjacent end 70 of the collar 8.

75 From the foregoing description of the various parts of the device, the operation thereof may be readily understood. My improved electrical binding terminal is especially well adapted for use upon instruments employed in a radio circuit where connection and disconnection between the instruments is desirable at will and also where positive connection must be assured. In securing a conductor such as a conductor 11 (see Figure 1) to the binding terminal, the collar 8 is first manually lowered upon the post 3 against the action of the spring 10. Of course the insulation 12 of the conductor 11 has been removed from the adjacent end of the conductor and the conductor is then disposed in one of the grooves 7. Pressure is then released from the collar 8 and the portion 9 of the collar causes the conductor to be tightly gripped between that portion of the collar and the depending wall of the mushroom head 6.

80 Let us assume now, as is shown in Figure 2, that a multiplicity of the conductors 11 are connected with the device in the manner shown. Because of the fact that the collar 8 is free to move vertically upon the post and to tilt slightly a pressure upon each of the conductors 11 will be substantially the same 85 due to equal distribution of the forces of the spring 10. This effect is usually true where no more than 3 conductors are employed and is an advantage not found in the ordinary binding terminal.

90 Another and important advantage of my binding terminal is that a continuous conduc-

tor such as that shown at the right in Figure 2 may be connected to the terminal without the necessity of severing the conductor, thus increasing the resistance thereof.

- 5 In Figure 3 I have shown a modified form of my invention in which the upper of the nuts 5 is replaced with a cup shaped member 13 having depending shearing portions 14 which are for the purpose of biting into
10 the panel 1. This cup shaped portion 13 has a threaded bore 15 by means of which the member may be employed in the same manner as the nut 5 for which it is substituted.
15 The collar 8 is replaced by a collar 16 having depending side walls 17 in the form of an apron which overhangs the upstanding walls 18 of the cup shaped member 13, so as to entirely encase the spring 10 which is disposed
20 about the post 3 the same as in the preferred form. This form of my invention operates in precisely the same manner as the preferred form, but the construction while more costly has an extreme and neat appearance
25 and the spring is completely protected.

In Figure 4 I have shown a still further modified form of my invention which is intended to be constructed at an extremely low cost and in this form the post 3 has a reduced threaded portion 4 which is projected through the opening 2 of the panel 1 and a single nut 5 holds the post in place.

A head 19 is carried by the upper end of the post 3 constructed somewhat after the
35 fashion of the mushroom head 6 and a flat collar 20 is disposed concentric with the post 3 adjacent to the lower convoluted edge 21 of the head 19.

A single band spring 22 having its ends
40 overlapped at 23 is disposed upon the post 3 by means of holes punched through diametrically opposite sides of the band when coiled in the form shown in the drawing.

The operation of this modification of my
45 invention is also the same as that of the preferred form.

In Figure 5 I have shown still a further modified form of my invention in which the post 3 has a reduced portion 4 and is secured to the panel in precisely the same manner as 50 the form shown in Figure 4.

In this form of my invention the post 3 has an enlarged head portion 24. An opening 25 is provided transversely through the post 3 adjacent to the head 24 through which 55 a conductor 11 or the like may be projected.

A compression spring of the band type shown at 26 is disposed upon the post 3 in the same manner as the spring 22 in the form of the device shown in Figure 4. 60

The operation of this form of my invention consists of projecting the conductor through the opening 25 while the spring 26 is compressed manually. Upon releasing the spring 26 it will rise and engage with the 65 adjacent portions of the conductor 11 and hold the conductor in close engagement with the post 3.

I claim:

An electrical binding terminal of the character described comprising a post arranged to be fixed at its lowermost end to a supporting surface, a washer slidably mounted on said post and having an upwardly extending marginal flange, said post having an enlarged integral head portion at the uppermost end thereof, and a compression spring mounted concentric with said post between said washer and the lower end of said post for yieldingly holding said washer in close 80 engagement with said head, said head portion being provided with a depending marginal flange having a plurality of grooves equally spaced around the lower edge thereof, said grooves having arcuate-shaped upper surfaces whereby one or more conductors may be readily inserted therein from any angle and rigidly held in place, the arcuate-shaped surfaces of the grooves conforming to the conductors. 85

JOHN L. POLK.
